UNITED STATES PATENT OFFICE.

GRiffin P. TURNER AND HULAH U. HUFF, OF CHATTANOOGA, TENNESSEE.

DESIGN FOR A BOOSTER PLATE FOR AUTOMOBILE RADIATOR ORNAMENT OR SIMILAR ARTICLES.

Application filed June 2, 1928. Serial No. 26,984. Term of patent 7 years.

To all whom it may concern:

Be it known that we, GRIFFIN P. TURNER and HULAH U. HUFF, citizens of the United States, residing at Chattanooga, in the county of Hamilton and State of Tennessee, have invented a new, original, and ornamental Design for a Booster Plate for Automobile Radiator Ornament or Similar Articles, of which the following is a specification, reference being had to the accompanying drawing, forming part thereof.

Figure 1 is a view in front elevation of the booster plate for automobile radiator ornament or similar article;

Figure 2 is a view in edge elevation.

We claim:—

The ornamental design for a booster plate for automobile radiator ornament or similar articles, as shown.

GRiffin P. TURNER.
HULAH U. HUFF.
